RECORD CONTROLLED MUSICAL INSTRUMENT

Filed Dec. 3, 1923

UNITED STATES PATENT OFFICE.

TOLBERT F. CHEEK, OF NEW YORK, N. Y., ASSIGNOR, BY MESNE ASSIGNMENTS, TO WELTE COMPANY, INC., OF NEW YORK, N. Y., A CORPORATION OF DELAWARE.

RECORD-CONTROLLED MUSICAL INSTRUMENT.

Application filed December 3, 1923. Serial No. 678,219.

The volume of tone emitted from record controlled musical instruments of pneumatic nature depends upon the tension of the air existing within the wind chest at the moment the tone is sounded.

One of the important purposes of this invention is to provide a record controlled musical instrument with adequate expression control means which responds to changes in the air tensions within the system brought about under control of the operator. Particularly, it is an important purpose of the invention to provide a record controlled musical instrument with means whereby a crash effect followed immediately by a pianissimo volume of tone, for example, may be produced under control of the operator.

The invention finds its most beneficial application in that type of record controlled musical instruments—pianos, especially—wherein the necessary wind tensions within the system are produced by means which are operated with varying force, as by pedals, for example.

I have, therefore, illustrated a preferred form of the invention when applied to a pedal operated player mechanism for pianos, and while I shall confine the following description to this particular form and application of the invention, I would have it understood that the invention embodies features which are not restricted to its application to a piano, or to the employment of pedal operated pumping means, and, generally, that changes in details may be made, all without departing from the spirit of the invention as defined by certain of the appended claims. Again, I have in the illustrated embodiment of the invention shown the parts so correlated that they operate upon the suction principle, this being at present customary in record controlled pneumatically operated player mechanisms for pianos, but it is well understood that the pressure principle—that is, an arrangement of parts in which the pumping means raises the pressure of the air above that of the atmosphere instead of reducing it below atmospheric pressure—may be employed, even in piano playing mechanisms, and is customarily employed for certain instruments, (organs, for example,) and those skilled in the art may readily adapt the present

mechanism to the pressure principle without departing from its spirit or the scope of appended claims.

In that type of pneumatically operated player mechanisms wherein the tension of the air is controlled by pedal operated means, the means heretofore provided for varying the air tension under control of the pedals have not been such as to enable the operator to so control the air tensions at all times from his operation of the pedals that the volume of tone or tones emitted will be that called for by a proper rendition from a musician's standpoint of the composition being played. In other words, instruments of this class heretofore manufactured have not been sufficiently responsive to the operations of the pedals to enable the operator fully and instantaneously to command from the pedals the volume of tone of every note or chord. He has been enabled in a general way to strengthen or reduce the air tension within the system by pumping faster or slower, but (referring now especially to pianos) reliance for an approximately correct expression has been placed mainly on the proper operation of "loud" and "soft" buttons for the treble and bass, respectively, the operation of which buttons by varying the size of the openings through which the wind passes affect to that extent and in that way, the volume of tone emitted in the entire treble portion or the entire bass portion of the instrument. Such means, however, have been totally inadequate to a really musical rendition of the composition being played, the result being highly unsatisfactory and indeed displeasing to the trained musical ear in all cases in which the beauty of the composition depends in any wise upon the tonal strengths which may be summed up in the word "expression".

A further purpose of my invention, therefore, is to provide a foot operated mechanism for record controlled musical instruments, in which the volume of tone to be given any particular note or notes is so controlled that the intended and true musical expression may be derived from the operation of the pedals, merely by depressing the pedals partially or fully, or slow or fast, in accordance with the volume of tone to be produced at that moment.

In other words, this particular purpose of

the present invention is to provide means operative under control of the foot pedal or 5 pedals of the player mechanism to so regulate the expression that a musical rendition will be possible, the mechanism including for this purpose means so correlated with the 10 pedals and with the wind passage of the player mechanism that crash effects, crescendos, decrescendos, and any volume of tone from and including pianissimo and fortissimo, may be produced at any time by corresponding operation of the pedal or 15 pedals at that time.

Other purpose of the invention will be apparent to those skilled in this art from the 20 following description of the preferred embodiment thereof.

In the drawings, wherein like characters 25 of reference denote corresponding parts:

20 Fig. 1 is a diagrammatic view, with parts in section, showing a pedal operated piano playing mechanism embodying my improvements and

25 Fig. 2 is a perspective view showing the pedals, the pumping bellows, the reservoir bellows, and the wind passage between the pumping bellows and reservoir bellows, the wind passage and reservoir bellows being in section to disclose parts within them.

30 The tracker bar A, the valve box B, the striker pneumatics C, and the piano action D may be of usual and well known construction, and their illustrated correlation is a typical one when the player mechanism 35 is mounted within the casing of an upright piano and is arranged to operate upon the piano action, directly: the drawing showing a duct 10 which extends from the tracker aperture 11 to a chamber 12 in the valve box; a separate duct 13 which extends from a chamber 14 in said valve box to the interior of the corresponding striker pneumatic C; a valve 15 in said chamber 14, connected to an operating pneumatic 16 and 40 controlling ports 17 and 18, through one of which (17) the chamber 14 and, hence, the interior of the striker pneumatic, has communication with the atmosphere and through the other of which (18) said chamber 14 and interior of said pneumatic has 45 communication with a wind passage 19 in the valve box B. It will be understood that in practice there is a separate tracker aperture 11, duct 10, chamber 12, pneumatic 16, valve 15, chamber 14, duct 13 and striker pneumatic for each note within the range 50 of the player mechanism, and that the wind passage 19 is common to all the notes, although it may, if desired, be divided into 55 separate sections for the bass and treble, respectively.

The drawings also shows pedals E and F which, similarly, may be of the usual, or 60 any suitable, construction commonly employed in foot operated pumping mecha-

nisms for producing the necessary exhaust tension within the wind passage 19 and other parts of the player mechanism. The pump may be of any construction suitable for the purpose: the one illustrated being 70 of a well known style composed of two bellows G and H, having their movable members 20 and 21, respectively, connected by arms 22 and 23 with the free ends of the 75 pedals E and F, which pedals in operation turn pivotally about an axis, at 24, and are provided with springs 25 and 26 which are placed under tension by the depression of the respective pedals and operate to return the pedals to their outer or raised positions. 80 The interior of the pumping pneumatics G and H have communication with the wind passage 19, through ports 27, a wind passage 28 and a duct 29. The wind passage 28 is formed in a member 28' to one side of 85 which the pumping pneumatics G and H are attached. The ports 27 are closed by flap valves 30 which open inward into the respective pneumatics G and H. These 90 pneumatics also have outwardly open flap valves 31 for the escape of the air therefrom.

It will be understood that in the operation 95 of the mechanism the admission of air at atmospheric pressure to any one of the chambers 12 by the registration of a perforation in a note sheet (not shown) with the corresponding tracker aperture 11, will cause the membrane 16 adjacent said chamber 12 to be inflated and thereby to move 100 the corresponding valve 15 to open the suction port 18 and close the atmospheric port 17 controlled by said valve. The corresponding striker pneumatic C is thereupon 105 collapsed in accordance with the exhaust tension at this moment existing in the wind passage 19. The movable member 32 of the striker pneumatic, here shown, has an arm 33 which operates upon a member 34 of the piano action D, so that when the striker 110 pneumatic is collapsed the corresponding note is struck. When the perforation of the note sheet which opened the aperture 11 has passed by said aperture and the latter has thereby been closed, the tension of the 115 air in the corresponding chamber 12 is again rarefied, through the bleed hole 19', whereupon the valve 15 will return to its former position in which it closes the suction port 18 and opens the atmospheric port 17. Air at atmospheric pressure will now 120 be admitted to the interior of the striker pneumatic C and the latter will thereupon quickly be returned to its expanded condition by the flushing action of the atmospheric air and the spring 35.

A reservoir of a suitable nature, as the bellows I having a spring i for expanding it, has communication with the wind passage 28 through a plurality of separately 125

controlled ports, marked 36 and 37, respectively. A valve 38 is so correlated with the port 36 that the air will flow through said port between the wind passage 28 and the reservoir in one direction only. A flap valve is preferred for this purpose. The port 37 is controlled by a valve which is of a nature such that it permits air to pass through the port 37 in both directions between said air passage and the interior of the reservoir. This valve is preferably provided (or carried) by the movable member 39 of a pneumatic 40. This pneumatic 40 is provided with a light spring 42, for expanding it and with an opening or port 43. The valve 38 and the pneumatic 40 are shown as mounted within the reservoir I, this being the proper location thereof when the parts are arranged to be operated on the suction principle. The capacity of the wind passage 28 is much less than that of the reservoir I, for a purpose which will be presently set forth.

The function of the valve 38 is to maintain in the wind passages which are in open communication with the interiors of the striker pneumatics, a wind tension which is never less than that in the reservoir I, and it assures that there shall be no weakening of individual tones below that desired, even when a number of striker pneumatics are operated simultaneously. Slight changes in the wind tensions within said passages, such as would be consequent upon the collapse of a single striker pneumatic, (or perhaps two or may be three pneumatics at once, in certain instances,) may be taken care of by the valve which controls the port 37. The principal, if not the exclusive, function of the latter valve, however, is to restrict the passage through said port whenever the tension is substantially greater in the wind chest than in the reservoir.

In other words—referring now particularly to the illustrated embodiment of the invention:—

The valve 38 is so arranged that it closes the port 36 when the exhaust tension in the passage 28 is greater than that in the reservoir, and will open said port instantaneously upon a reduction of the exhaust tension in the passage 28 below that in the reservoir and again close said port as soon as the exhaust tension in said passage has been again raised. It overcomes the effect which would otherwise result from the weakening of the exhaust tension and consequent rise in pressure in the exhaust system between and including the wind passage 28 and the striker pneumatics, due to the operation of the latter. It will be understood that such weakening of the exhaust tension is in proportion to the number of striker pneumatics operated at the same time and is a natural consequence of leakage within the system. In

short, this valve maintains the strength of tone predetermined by the pumping operation, even though a large number of striker pneumatics be operated simultaneously.

The valvular means which operates with relation to the port 37, (the valvular member of which is here shown as provided by a felt pad 41 fixed to the movable member 39 of the pneumatic 40) is so correlated with said port and with the wind passage 28 and reservoir I that the tendency is for the pneumatic 40 to collapse and restrict the flow of air through the port 37 whenever there is a substantial increase of the strength of the exhaust tension in the wind passage 28 above that in the reservoir I, without, however, completely cutting off the flow of air through said port at any time. The spring 42 of said pneumatic is placed under tension by the collapsing movement of the pneumatic and becomes operative to expand the pneumatic 40 as soon as the strength of the exhaust tension in the wind passage 28 is reduced to the point where the pressure in said passage plus the spring can overcome the pressure in the reservoir. It, therefore, becomes possible with this means to produce a rapid increase in the strength of the exhaust tension in the wind passage 28—to produce a crash effect, for example—and then instantly to vent said passage to an extent at which a pianissimo strength of tone is produced, for example, merely—in this embodiment of the invention—by forcibly depressing both pedals at the same time and then releasing pressure thereon. The forcible depression of both pedals rapidly increases the strength of the exhaust tension in the wind passage 28 and collapses the pneumatic 40; the collapsing of said pneumatic contributing to rapidity of the increase of said exhaust tension by substantially cutting down the flow of air between the reservoir I and said wind passage. Notes which are now struck produce a crash effect. Immediately following the production of the crash effect, there is a rapid weakening of the exhaust tension in the wind channel, due in part to leakage and substantially contributed to by the fact that at this time the 115 pedals are returning to their raised positions and are consequently not pumping.

Due to these conditions and to the fact that the capacity of the wind channel is small compared to the capacity of the reservoir, the air from the reservoir passing the valve through the port 37 immediately lessens the tension in the wind channel by raising the pressure therein. This permits the spring 42 to expand the pneumatic 40 with a result that the wind channel is flushed and the pressure equalized between the reservoir and wind channel. This flushing of the wind channel has no substantial effect on the pressure within the reservoir due to 130

the relatively small size of the wind channel.

This reduction of the tension in the wind channel and restoration of the equalization of pressure between the reservoir and wind channel, takes place in such a short period of time that, as already suggested, a crash effect may be obtained and the same followed immediately by a pianissimo or any other gradation of tone, the volume of this tone depending upon whether or not the pedals are immediately operated again and the speed at which they are operated.

It is not essential to the invention, considered in its broad aspects, what particular means are provided to prevent the full closure of the port 37, but it is advantageous that provision be made for variably defining the extent of such closure. To this end, I have provided an adjustable stop 44 arranged in the path of closing movement of the valve member 41, and preferably provided with a covering of soft material, 45, as leather, for example, to contact with the valve member 41. When said valve member 41 is also of soft material, and to a lesser extent when either but not both the valve and the stop have their surfaces for contact with each other formed of soft material, the noise which would otherwise be produced by impact of the valve with the stop is deadened, and, moreover, there might be leakage between them even when the pneumatic 40 is collapsed, but the amount of such leakage could not be regulated without provision for relative adjustment of the stop and valve. Therefore, the stop, as here shown, is preferably arranged at one end of a rod 46, which has a threaded engagement, at 47, with a stationary member 48, and has at its end opposite the stop a knurled head 49 for convenience in turning it to adjust the stop.

While I have entitled this invention, record controlled musical instruments, and have illustrated an embodiment thereof in which the pedals are connected to the casing of the instrument and the player mechanism is arranged in said casing, it will be apparent that it is equally applicable to that type of player mechanisms which are mounted in a cabinet or the like which is movable relatively to the instrument to act upon the latter. In short, the invention relates particularly to certain parts of player mechanisms and comprehends within its scope the improvements made therein, whether said parts are actually arranged within the confines of the case of the musical instrument or in a case or cabinet, or container or support of any appropriate kind outside the musical instrument itself.

What I believe to be new and desire to secure by Letters Patent, is:—

1. A record controlled player mechanism for a musical instrument comprising, in combination, means providing an unrestricted

passage for wind, means for producing wind tension within said passage, a reservoir, the reservoir and wind passage having ports therebetween, and control valves for said ports, respectively, one of said valves being operative to open its port whenever the tension in the wind passage tends to become less than the tension in the reservoir and the other of said valves being operative to restrict without closing the passage through its port whenever the tension is substantially greater in the wind passage than in the reservoir.

2. A record controlled player mechanism for a musical instrument comprising, in combination, means providing an unrestricted passage for wind, means for producing wind tension within said passage, a reservoir, the reservoir and wind passage having ports therebetween, and control valves for said ports, respectively, one of said valves permitting the air to pass in one direction only and the other valve permitting the air to pass in opposite directions and means for preventing the latter valve from closing entirely.

3. A record controlled player mechanism for a musical instrument comprising, in combination, means providing an unrestricted passage for wind, means to produce wind tension within said passage, a reservoir having connection with the wind passage, and means including a pneumatic having its opposite sides subjected to the air tension in the reservoir and wind passage respectively and controlling the pressure within the latter.

4. A record controlled player mechanism for a musical instrument comprising, in combination, means providing a passage for wind, means for producing wind tension within said passage, a reservoir, and operative connections between the wind passage and reservoir, including a control valve operative to permit the air to pass in one direction only, to maintain in the wind passage a tension which is not less than the tension in the reservoir, regardless of the number of notes simultaneously sounded.

5. A record controlled player mechanism for a musical instrument comprising, in combination, means providing a passage for wind, means for producing wind tension within said passage, a reservoir, and means to control communication between the reservoir and wind passage including a normally closed flap valve whose opposite sides are subjected to the tensions in the wind passage and reservoir, respectively, and operative to maintain in the wind passage, a tension which is not less than the tension in the reservoir.

6. A record controlled player mechanism for a musical instrument comprising, in combination, means providing a passage for wind, a pumping means having communica-

tion with said passage, a reservoir, the wind passage and reservoir having means through which air may pass in opposite directions from either to the other, a pneumatically operable valve operatively related to the latter means and having its opposite sides subjected to the air pressure in the wind passage and reservoir, respectively, and controlling the flow of air between said wind passage and reservoir and an adjustable stop for arresting the valve at any one of a plurality of positions.

7. A record controlled player mechanism for a musical instrument comprising, in combination, means providing a passage for wind, a pumping means to produce wind tension within said passage, a reservoir, the wind passage and reservoir having means through which air may pass in either direction from one to the other, and a pneumatically operable valve operative to control the wind pressure in said passage and restrained against completely closing the communication between the wind passage and reservoir.

8. A record controlled player mechanism for a musical instrument comprising, in combination, means providing a passage for wind, a pumping means having communication with said passage, a reservoir, means through which air may pass in either direction between the wind passage and reservoir, and a pneumatically operable valve: the parts so correlated that the valve will restrict the flow of air in one direction through the last mentioned means, without at any time completely cutting off the communication between the reservoir and wind passage.

40 9. A record controlled player mechanism for a musical instrument comprising, in combination, means providing a passage for wind, a pumping means to produce wind tension within said passage, a reservoir, the wind passage and reservoir having means through which air may pass in either direction from one to the other, a pneumatically operable valve operative to control the wind pressure in said passage and a stop so correlated with the valve that it will prevent the complete closure of the valve.

10. A record controlled player mechanism for a musical instrument comprising, in combination, means providing a passage for wind, a pumping means to produce wind tension within said passage, a reservoir, the wind passage and reservoir having means through which air may pass in either direction from one to the other, a pneumatically operable valve operative to control the wind pressure in said passage and an adjustable stop so correlated with the valve that it will prevent the complete closure of the valve.

65 11. A record controlled player mechanism for a musical instrument comprising in com-

bination, means providing a passage for wind, pumping means to produce wind tension within said passage, a reservoir, the wind passage and reservoir having means through which the air may pass in either direction from one to the other, and a pneumatic operatively related to the last mentioned means and carrying a valvular member of soft material and means preventing the valvular member from entirely shutting off the passage of air.

12. A record controlled player mechanism for a musical instrument comprising, in combination, means providing a passage for wind, pumping means to produce wind tension within said passage, a reservoir, the wind passage and reservoir having means through which the air may pass in either direction from one to the other, a pneumatic operatively related to the last mentioned means and provided with a valvular member of soft material, and a stop to engage said valvular member to prevent the complete closure of said last mentioned means.

13. A record controlled player mechanism for a musical instrument comprising, in combination, means providing a passage for wind, pumping means to produce wind tension within said passage, a reservoir, the reservoir and wind passage having means through which the air may pass in either direction from one to the other, a pneumatic operatively related to the last mentioned means and provided with a valvular member of soft material, and a stop having a surface of soft material to engage said valvular member and operative to prevent the complete closure of said last mentioned means.

14. A record controlled player mechanism for a musical instrument comprising, in combination, means providing a passage for wind, means for producing in said passage a flow of air of variable tension, a reservoir, the wind passage including a member having a much smaller capacity than that of the reservoir, and means for controlling communication between said member and the reservoir, including a port and a pneumatically controlled valve operatively related to the port to restrict without entirely closing the port when there is a strong increase of the tension in said member and to open the port and permit flushing of said member from the reservoir when the tension is reduced.

15. A record controlled player mechanism for a musical instrument comprising, in combination, means providing a passage for wind, means for producing in said passage a flow of air of variable tension, a reservoir, the wind passage including a member having a much smaller capacity than that of the reservoir, and means for controlling communication between said member and the reservoir, including a port and a pneumatic

operatively related to the reservoir and to said member to restrict without entirely closing the port when there is a strong increase of the tension in said member and to open the port and permit flushing of said member from the reservoir when the tension is reduced.

16. A record controlled player mechanism for a musical instrument comprising, in combination, means providing a passage for wind, means for producing in said passage a flow of air of variable tension, a reservoir, the wind passage including a member having a much smaller capacity than that of the reservoir, and means for controlling communication between said member and the reservoir, including a port and a bellows arranged in and having an opening to the reservoir and whose interior is open to said member through said port, said bellows having a member to restrict the port when the bellows is collapsed and means for preventing the closing of the port.

17. A record controlled player mechanism for a musical instrument comprising, in combination, means providing a passage for wind, pedal operated means for producing wind tension within said passage, a reservoir, the reservoir and wind passage having ports therebetween, and control valves for said ports, respectively, one of said valves being normally closed and operative to open its port whenever the tension in the wind passage tends to become less than the tension in the reservoir and the other of said valves being operative to restrict but not close the passage through its port when the tension is substantially greater in the wind chest than in the reservoir.

18. A record controlled player mechanism for a musical instrument, comprising, in combination, striker pneumatics, means providing a passage for wind, pedal operated means for producing wind tension in said passage, means under control of a record to control communication of said passage with the striker pneumatics, a reservoir, means through which the air may pass in either direction between the wind passage and reservoir, and a pneumatically operable valve correlated with the last mentioned means and with said reservoir and wind passage to restrict the flow of air in one direction through said means without at any time completely cutting off communication between the reservoir and wind passage.

19. A record controlled player mechanism for a musical instrument comprising, in combination, striker pneumatics, means providing a passage for wind, a pedal operated pumping means to produce wind tension in said passage, means under control of a record to control communication of said passage with the striker pneumatics, a reservoir, the wind passage and reservoir having

means through which air may pass in either direction from one to the other, and a pneumatically operable valve operative to control the wind pressure in said passage and restrained against completely closing the communication between the wind passage and reservoir.

20. A record controlled player mechanism for a musical instrument comprising, in combination, striker pneumatics, means providing a passage for wind, a pedal operated pumping means to produce wind tension within said passage, means under control of a record to control communication of said passage with the striker pneumatics, a reservoir, means through which air may pass in either direction between the wind passage and reservoir, a pneumatically operable valve to control the wind pressure in said passage, and a stop so correlated with the valve that complete closure of the valve will be prevented.

21. A record controlled player mechanism for a musical instrument comprising, in combination, striker pneumatics, means providing a passage for wind, a pedal operated pumping means to produce wind tension within said passage, means under control of a record to control communication of said passage with the striker pneumatics, a reservoir, means through which air may pass in either direction between the wind passage and reservoir, a pneumatically operable valve of soft material to control the wind pressure in said passage, and a stop to contact with said valve to prevent complete closure of the same.

22. A record controlled player mechanism for a musical instrument comprising, in combination, striker pneumatics, means providing a passage for wind, a pedal operated pumping means to produce wind tension within said passage, means under control of a record to control communication of said passage with the striker pneumatics, a reservoir, means through which air may pass in either direction between the wind passage and reservoir, a pneumatically operable valve of soft material to control the wind pressure in said passage, and a stop having a surface of soft material to contact with said valve to prevent complete closure of the same.

23. A record controlled player mechanism for a musical instrument comprising, in combination, striker pneumatics, means providing a passage for wind, pedal operated means for producing in said passage a flow of air of variable tension, means under control of a record to control communication of said passage with the striker pneumatics, a reservoir, the wind passage including a member having lesser capacity than that of the reservoir, and means to control communication between said member and the reservoir including a port and a pneumatically con-

trolled valve operatively related to the port to restrict without entirely closing the port when there is a strong increase of the tension in said member and to open the port and permit flushing of said member from the reservoir when the tension is reduced.

24. A record controlled player mechanism for a musical instrument comprising, in combination, striker pneumatics, means providing a passage for wind, pedal operated means for producing in said passage a flow of air of variable tension, means under control of a record to control communication of said passage with the striker pneumatics, a reservoir, 10 the wind passage including a member having a much smaller capacity than that of the reservoir, and means to control communication between said member and the reservoir including a port and a pneumatic operatively 15 related to the port to restrict without entirely closing the port when there is a strong increase of the tension in said member and to open the port and permit flushing of said member from the reservoir when the tension 20 is reduced.

25. A record controlled player mechanism for a musical instrument comprising, in combination, striker pneumatics, means providing a passage for wind, pedal operated means 30 for producing in said passage a flow of air of variable tension, means under control of a record to control communication of said passage with the striker pneumatics, a reservoir, the wind passage including a member having 35 less capacity than that of the reservoir, and means to control communication between said member and the reservoir, including a bellows arranged in and having an opening to the reservoir and whose interior 40 is open to said member through said port, said bellows having a valvular member to restrict the port when the bellows is collapsed, and a stop having a threaded adjust-

ing means for controlling the degree of restriction.

26. A record controlled player mechanism for a musical instrument comprising, in combination, striker pneumatics, means providing a passage for wind, pedal operated means for producing in said passage a flow of air 45 of variable tension, means under control of a record to control communication of said passage with the striker pneumatics, a reservoir, the wind passage including a member having a less capacity than that of the reservoir, and means to control communication between said member and the reservoir including a bellows arranged in and having an opening to the reservoir and whose interior is open to said member through said port, said bellows having a valvular member of soft material to restrict the port when the bellows is collapsed and a stop having a threaded adjusting means for controlling the degree of restriction. 50 55 60 65

27. A record controlled player mechanism for a musical instrument comprising, in combination, striker pneumatics, means providing a passage for wind, pedal operated means for producing in said passage a flow of air of 70 variable tension, means under control of a record to control communication of said passage with the striker pneumatics, a reservoir, the wind passage including a member having less capacity than that of the reservoir, and 75 means to control communication between said member and the reservoir including a bellows arranged in and having an opening to the reservoir and whose interior is open to said member through said port, said bellows having a valvular member of soft material and a stop to engage said valvular member, to assure the incomplete closure of 80 the port.

In testimony whereof I affix my signature.
TOLBERT F. CHEEK.
